UNITED STATES PATENT OFFICE.

WILLIAM P. HARMONY, OF SIDNEY, OHIO.

FEED-GUIDE FOR PRINTING-PRESSES.

1,074,861.

Specification of Letters Patent.

Patented Oct. 7, 1913.

Application filed September 11, 1912. Serial No. 719,832.

To all whom it may concern:

Be it known that I, WILLIAM P. HARMONY, a resident of Sidney, in the county of Shelby and State of Ohio, have invented 5 certain new and useful Improvements in Feed-Guides for Printing-Presses; and I do hereby declare the following to be a full, clear, and exact description of the invention, such as will enable others skilled in the art 10 to which it pertains to use the same.

This invention relates to feed guides for platen printing presses, that is, to guides or gages of the character secured to the tympana of such presses to insure correct positioning and the holding of sheets as they are 15 fed to the press.

The object of the invention is to provide such a guide of great simplicity, effectiveness, and without movable parts or parts 20 liable to be bent or broken.

The invention consists in the construction hereinafter described and particularly pointed out in the claims.

In the accompanying drawing which illustrates the invention and forms part of the specification;—Figure 1 is an enlarged side elevation of the guide secured to a tympan, the latter being shown in section; Fig. 2 is a plan view of the same; Fig. 3 is a plan 25 view of a blank such as used for making the guide.

In making the improved guide I employ a plain straight blank 1 of brass, copper, or other suitable material, preferably cutting it 30 from a longer strip, or a sheet, and bending the blank into final shape at a single operation. In Fig. 3 the three transverse broken lines denote the location of the required bends.

40 The guide, which is complete in itself, comprises a main flat part 2, which in use is connected to a press tympan by any suitable adhesive material, a part 3 extending upward and a little forward, a reversely bent part 4, and a front foot 5 in, or nearly in, the plane of part 2. The parts 3 and 4 brace 45 each other and are not liable to be accidentally bent out of position. The corners

of the blank are shown clipped; this is not essential but is preferred, especially at the 50 front end since it assists in placing the guide on a tympan as hereinafter described.

Numeral 6 denotes a tympan such as suitable for use in a press of the character stated. The top or draw sheet 9 of the tympan where a guide is to be located has accurately cut therein a slit 7 a little longer than the width of the guide, and into this slit the foot 5 is entered until the part 4 reaches the front edge of the slit which exactly locates the guide and that without requiring either skill or judgment on the part of the workman. The slit 7 being cut by a sharp instrument, and the foot 5 entering easily therein, no ragged edges or parts, 60 such as might interfere with movement of the sheet fed, are formed, as in some cases in which guides are formed with projections which themselves puncture the tympan. The foot 5 extends entirely across the 65 guide and therefore when it is entered in the slit 7 it protects the whole width of the guide against the fed paper working under the guide so as to permit a crooked feed. The upwardly projecting part of the guide, 70 which inclines toward the operator, guides the fed sheet downward and with the small overhanging loop 8 tend to keep it from curling up and slipping over the guide.

This simple device has no movable or adjustable parts, and no pins, screws, or the like, to get out of adjustment, break or be lost.

The invention is not limited to the exact form shown. For example, although it is 85 preferred to have the edges of the blank and of the guide parallel this is not essential. Nor is it essential that the parts 3 and 4 be parallel, nor that part 3 incline forward.

Having thus described the invention what 90 I claim and desire to secure by Letters Patent of the United States is;—

1. A guide for fed sheets in platen printing presses comprising a continuous strip of metal having a main flat body portion, a 95 double upward and forwardly inclined ex-

tension, and a front foot in substantially the plane of the body portion and extending clear across the guide.

2. A guide for fed sheets comprising a single strip having a supporting body portion, an upward extension against which fed sheets bear, there being a loop or bend at the top and overhanging on the front side of said extension, and a foot as wide as said body portion and in substantially

the plane thereof in advance of the lower end of said upward extension below the bearing portion for said fed sheets.

In testimony whereof, I have signed this specification in the presence of two subscribing witnesses.

WILLIAM P. HARMONY.
